FIG. 1

FIG. 2

FIG. 3

FIG. 4

FIGURE 1 is a top plan view of a box, showing my new design;

FIGURE 2 is a side elevational view of the bottom section thereof with the lid removed;

FIGURE 3 is a bottom plan view of the bottom section thereof; and

FIGURE 4 is an enlarged vertical sectional view taken on the plane of line 4-4 of FIGURE 3.

The box comprises two sections in which an annular, peripherally flanged lid is received on and conforms to the upper annular, indented portion of the bottom section shown in FIGURE 2.

The characteristic feature resides in the combination on the container shown of the bottom section having a

double, downwardly-opening side wall construction in which the outer wall is circumferentially fluted, as best shown in FIGURE 4 of the drawing.

I claim:

The ornamental design for a box, as shown and described.
